UNITED STATES PATENT OFFICE

103,046

DESIGN FOR A SIGN

Arthur R. Ellis, Cedar Rapids, Iowa

Application November 21, 1936, Serial No. 66,078

Term of patent 3½ years

To all whom it may concern:

Be it known that I, Arthur R. Ellis, a citizen of the United States, residing at Cedar Rapids, in the county of Linn and State of Iowa, have invented a new, original, and ornamental Design for Signs, of which the following is a specification, reference being had to the accompanying drawing, forming part thereof.

The figure is a perspective view of a sign, showing my new design. The sign appears the same from the opposite side.

I claim:

The ornamental design for a sign as shown and described.

ARTHUR R. ELLIS.
